GAS BURNER

Edwin H. Kahler, Taunton, Mass., assignor to
Glenwood Range Company, Taunton, Mass., a
corporation of Massachusetts

Application July 19, 1933, Serial No. 681,087

2 Claims. (CL. 158—117)

This invention relates to improvements in the round or circular type of gas burners.

Gas burners consisting of a round or cup-shaped outer member and a circular centre member arranged to provide an annular gas discharge slot between the two members have been proposed heretofore, but in these prior constructions the walls of the gaseous chamber leading to the gas discharge slot have been provided with ribs, shoulders or apertures which tend to produce turbulent effects in the gaseous stream delivered to the discharge slot.

The present invention contemplates a round burner which is so constructed that the gaseous fuel and the secondary air supplied to support combustion are delivered to the point of combustion so as to eliminate as far as possible all forms of eddy currents and turbulent effects in the gas and air streams.

An important feature of the invention resides in a gas burner comprising a cup-shaped head having a tubular centre member mounted therein so as to provide an annular mixing chamber therebetween having a circular discharge slot, the walls of which chamber are so formed that they are free from apertures, projections and irregular surfaces that would produce turbulent effects in the gaseous stream.

A more specific feature of the invention resides in a round burner which is so constructed that the annular walls of the gaseous chamber are shaped so that they are curved in an axial direction and converge toward each other in the direction of the discharge slot to provide smooth curved walls that will direct the gaseous stream to the discharge slot with a minimum amount of disturbance.

A further feature of the invention resides in a round burner which is so constructed that secondary air is supplied to the point of combustion through an inner outwardly flaring member of tubular construction, the walls of which member are formed with a smooth outwardly curved surface adapted to effect a uniform distribution of this secondary air to the point of combustion.

Another feature of the invention resides in an improved means for obtaining a precise adjusted opening of the discharge port of the burner.

As a result of the construction of the present invention a highly efficient burner is provided, the flame of which burns very evenly and causes the heat to spread out over the bottom of a cooking utensil with a substantially uniform action.

The above and other features of the invention and novel combination of parts will be herein-after described in connection with the accompanying drawing which illustrates one good, practical form of the invention.

In the drawing:

Fig. 1 is a top plan view of a round burner constructed in accordance with the present invention and secured to a mixing tube.

Fig. 2 on a larger scale is a side view of the burner of Fig. 1; and

Fig. 3 is a vertical sectional view through the burner of Fig. 2.

In the embodiment of the invention shown the burner is provided with a cup-shaped head 10, the upper portion of which flares outwardly as indicated at 11. The head 10 has a central hole formed in its bottom and this hole is preferably threaded as at 12. The head is also provided with the laterally extending boss 13 having a threaded opening formed therein and adapted to receive the threaded end of a mixing tube 14. The mixing tube 14 may be of usual construction and is provided at its large intake end with the usual air regulating valve 15.

Within the cup-shaped head 10 is mounted the tubular member 16 the lower end of which is threaded to engage the threads 12 of the head, and the upper portion of the member 16 flares outwardly as at 17 to overlie the upper end of the head 10. The arrangement is such that a narrow circular discharge port is formed between the upper end or lip 18 of the head and the overhanging lip 19 of the tubular member 16. The lower face of the lip 19 preferably extends some distance in a horizontal plane as shown to direct the gaseous mixture outwardly in a horizontal direction at the point of ignition. This construction permits the burner to be placed near the bottom of the cooking vessel and prevents the slot from being clogged by spillage.

The width of the discharge port between the lips 18 and 19 of the respective members may be varied as desired by turning the interior member 16 to rotate the threaded lower end of this member within the threads 12 of the exterior member or head 10. For then locking the parts in their adjusted position, in order that any determinate opening of the port may be maintained, set screws 20 are provided. These screws pass through the bottom of the exterior member outside the threaded connection between the two members with heads accessible from outside the

burner. The screws tighten against an exterior body flange 21 on the interior member adjacent the threaded connection between the members, and on tightening the screws the two members become locked together for maintaining the opening or port between them. Three screws are preferably employed, circumferentially arranged, and in proper spaced relation.

A further advantage of the screws 20 resides in the fact that these screws may be employed not only to maintain but, also, to obtain a precise adjustment of the port opening between the two members. If the threaded connection between the members is relied upon to obtain said opening, this threaded connection must be a relatively tight connection and be made with great precision for it is necessary that the width of the port be uniform throughout. Heat may sometimes cause some distortion, slightly varying the width of the port. To avoid the necessity of absolute precision in the threaded connection between the two members this connection may be made a relatively loose threaded connection and the screws be relied upon to obtain and maintain a precise adjustment in the width of the port opening between the members after said opening has been roughly obtained by the threaded connection between them. The screws may, also, be depended upon to cure any difficulty that may arise through distortion of the members by heat.

The construction of the head 10 and tubular member 16 is such that when they are assembled as shown an annular mixing chamber 22 is provided in the lower portion of the head, and the walls leading upwardly from the chamber 22 are curved in an axial direction and converge in the direction of the discharge port as shown.

The upwardly converging walls of the chamber 22, it should be noted, are formed with smooth gradually curved surfaces that are free of apertures, ribs or shoulders that would disturb the gradual flow of the gaseous stream to the discharge port, and these walls blend gradually with the shape of the lips 18 and 19 to form a smooth continuous curve extending to the outer edge of the burner port. Furthermore the shape of the walls and lips just mentioned is preferably such that they converge continuously from the mixing chamber 22 to the outer edge of the port so that the width of the port is less at this outer edge than at any other point. The effect of this is to direct the gaseous mixture to the point of combustion with a high coefficient of discharge and to steady the flame and prevent it from flashing back.

The inner wall of the tubular member 16 is likewise made smooth and free from ribs or other projections and flares outwardly in an upward direction so that the secondary air that passes up through the lower end of the member 16 may gradually spread outwardly adjacent the walls of the tubular member as indicated by the arrows. The effect of this is to help keep the burner cool and to cause a uniform distribution of the secondary air beneath the cooking utensil and supply air to the curved portion of the flame. Secondary air moving upwardly around the outer portion of the head 10 as indicated by the arrows is supplied to the lower portion 70 of the flame.

Adjustment of the inner member 16 so as to provide a narrow discharge port such as shown in Fig. 3 tends to direct the flame outwardly in a horizontal direction, while a wider port adjustment such as shown in Fig. 2 increases the tendency of the flame to curl upwardly as shown in this view. The connection between the lower end of the inner member 16 and the base of the head 10 should be machined or otherwise accurately formed, and the lips 18 and 19 and adjacent walls should likewise be accurately formed so that when the parts are assembled they will form a smooth discharge port of uniform width around the burner.

It will be understood from the foregoing that the construction of the present burner is such that the primary air and gas supplied by the tube 14 is thoroughly mixed in the chamber 22, that this gaseous mixture is delivered to the discharge port with a minimum amount of turbulent effect, and that the secondary air passing upwardly through the tubular member 16 is uniformly distributed to the burner. As a result a highly efficient and steady burning burner is provided that produces a very uniform heat beneath the cooking utensil. Furthermore the smooth inner surface of the tubular member 16 and opening therethrough makes the burner easy to clean to remove grease or food particles that may lodge thereupon.

Having thus fully described my invention, I claim and desire to secure by Letters Patent of the United States:—

1. A gas burner comprising an exterior cup-shaped member having a central bottom opening and an outwardly flaring upper end portion presenting an out-turned annular lip, an interior tubular member making closed connection with said exterior cup-shaped member around the opening in the bottom thereof and formed with a curved outwardly flaring upper end portion presenting an out-turned annular lip co-operating with said first mentioned lip to form an annular, substantially horizontal, discharge port between them, said members otherwise co-operating with each other to form a mixing chamber between them having smooth, stream-lined, walls gradually converging to said annular port, and means through which a gaseous mixture may be delivered to said mixing chamber.

2. A gas burner comprising an exterior cup-shaped member having a bottom opening and an upper out-turned annular lip, an interior tubular member making closed threaded connection with said outer member around the opening in the bottom thereof, said interior member having, also, an exterior body flange adjacent said threaded connection and an upper out-turned annular lip, said members co-operating with one another to form a mixing chamber between them with outlet through an annular port between said lips of the respective members, and a number of set screws accessible from outside the burner passed through the bottom of said exterior member outside the threaded connection between said members and adapted to tighten against said flange on the interior member.

EDWIN H. KAHLER.
